(57) CLAIM

The ornamental design for a sports game, as shown and described.

DESCRIPTION

FIG. 1 is a perspective view of the sports game showing the claimed design;

FIG. 2 is a front view of the sports game as shown in FIG. 1;

FIG. 3 is a back view of the sports game as shown in FIG. 1;

FIG. 4 is a left-side view of the sports game shown in FIG. 1;

FIG. 5 is a right-side view of the sports game shown in FIG. 1;

FIG. 6 is a bottom view of the sports game as shown in FIG. 1; and,

FIG. 7 is a top view of the sports game as shown in FIG. 1. All the broken lines shown in the drawings, including the nets, depict portions of the sports game that form no part of the claimed design.

1 Claim, 7 Drawing Sheets
